ROTARY BLOTTING DEVICE

Filed April 18, 1946

UNITED STATES PATENT OFFICE

147,729

DESIGN FOR A ROTARY BLOTTING DEVICE

Ernst Johan Jens Henriksen,
Copenhagen, Denmark

Application April 18, 1946, Serial No. 128,727

Term of patent 14 years

(Cl. D74—1)

To all whom it may concern:

Be it known that I, Ernst Johan Jens Henriksen, a subject of the King of Denmark and a citizen of Copenhagen, Denmark, have invented a new, original, and ornamental Design for a Rotary Blotting Device, of which the following is a specification, reference being had to the accompanying drawings, forming part thereof.

Figure 1 is a side view.

Figure 2 is a front view and

Figure 3 is a plan view of the rotary blotting device, showing my new design.

I claim;

The ornamental design for a rotary blotting device, substantially as shown.

ERNST JOHAN JENS HENRIKSEN.
